(57) **CLAIM**

The ornamental design for a drawer face for a vertical file, a safe, or the like, as shown and described.

DESCRIPTION

FIG. 1 is a perspective view of the design.

FIG. 2 is a top view of the design.

FIG. 3 is a front elevational view of the design; and,
FIG. 4 is a side view of the design.

The broken line showing of a safe is for illustrative purposes only and forms no part of the claimed design.
